CLAIM

The ornamental design for an aroma lamp, as shown and described.

DESCRIPTION

FIG. 1 is a perspective view of an aroma lamp design showing my new design.

FIG. 2 is a front view of an aroma lamp.

FIG. 3 is a rear view of an aroma lamp.

FIG. 4 is a left side view of an aroma lamp.

FIG. 5 is a right side view of an aroma lamp.

FIG. 6 is a top view of an aroma lamp.

FIG. 7 is a bottom view of an aroma lamp; and,

FIG. 8 is a rear, bottom side perspective view of an aroma lamp.

The shading is not a feature of the design but is utilized to illustrate the surface contours of the aroma lamp design in the drawings.

The broken lines in the drawings depict portions of the aroma lamp that form no part of the claimed design.

1 Claim, 8 Drawing Sheets
